(57) **CLAIM**

The ornamental design for a gun vault, as shown and described.

DESCRIPTION

FIG. 1 is a right elevation view of a gun vault showing my new design in an open position, the opposite side being a mirror image of the shown;

FIG. 2 is a right elevation view thereof in a closed position, the opposite side being a mirror image of the shown;

FIG. 3 is a rear elevation view thereof;

FIG. 4 is a front elevation view thereof;

FIG. 5 is a top plan view thereof in an open position;

FIG. 6 is a bottom plan view thereof in an open position; and, FIG. 7 is an isometric view thereof.
